UNITED STATES PATENT OFFICE.

CHARLES ARGYLE TORRENCE, OF WINNIPEG, MANITOBA, CANADA.

GRAIN-CLEANER.

1,383,260.

Specification of Letters Patent. Patented June 28, 1921.

Application filed September 3, 1919, Serial No. 321,401. Renewed May 11, 1921. Serial No. 468,724.

To all whom it may concern:

Be it known that I, CHARLES ARGYLE TORRENCE, of the city of Winnipeg, in the Province of Manitoba, Canada, have invented certain new and useful Improvements in Grain-Cleaners, of which the following is the specification.

The invention relates to improvements in grain cleaning machines and the principal object of the invention is to provide a large capacity machine which will initially clean grain by utilizing specially controlled air currents and stationary screens, the machine being designed to pick up the grain from a wagon, hopper or such like through a pickup spout and to discharge the cleaned grain through a discharge spout and the undesirable material such as dirt, small seeds, chaff, dust, crushed grain, etc., to a further dirt collecting spout.

A further object of the invention is to construct the machine in a compact manner and with few moving parts and such that the screens can be readily changed to suit requirements.

A still further object is to provide a special feeder for feeding the partially cleaned grain from the vacuum box into the discharge pipe in a running stream and such that there can be no back pressure through the feeder to the vacuum box.

A still further object is to provide a special support for the feed spout which allows of it being easily moved by the attendant to accommodate the work in hand and also permits of the lengthening or shortening of the spout depending on the conditions existing.

With the above and more important objects and certain other minor objects in view the invention consists essentially in the arrangement and construction of parts hereinafter more particularly described and later pointed out in the appended claims, reference being had to the accompanying drawings in which:

Figure 1 is a side view of the complete machine and as it appears mounted on a carrying truck.

Fig. 2 is a plan view thereof.

Fig. 3 is a rear end view, the truck being omitted.

Fig. 4 is a front end view, certain parts being in vertical section and the swinging beam being removed.

Fig. 5 is a longitudinal sectional view through the machine with the swinging beam removed.

Fig. 6 is a detailed side view of the drive for the feeder.

Fig. 7 is a fragmentary plan view of the brackets which support the socket plate.

Fig. 8 is a vertical sectional view through the pivot block supporting the swinging beam, the section being taken at 8-8' Fig. 1.

Fig. 9 is an enlarged detailed horizontal sectional view through one side of the vacuum box, the section being taken at 9-9' Fig. 5.

In the drawings like characters of reference indicate corresponding parts in the several figures.

The cleaner is mounted on a truck embodying a supporting table or platform 1 carried by rear wheels 2 and front wheels 3, the axle 4 of the front wheels being pivoted in the ordinary manner to allow of the steering of the truck when moving from place to place.

On the rear end of the platform I mount the base 5 of a fan casing 6 containing a fan 7 which is carried by the fan shaft 8, one end of the fan shaft being fitted with a driving pulley 9. Above the fan casing I locate my vacuum box or casing 10 which is carried by suitably disposed front and rear sets of side legs 11 and 12 secured to the platform and to the sides of the box.

The body of the box is substantially rectangular and it is provided at the top with a door 13 located directly to the rear of an open bottomed cross hood 14 fitted on the top side with a sight opening 15, the sight opening being closed with glass or other similar transparent material. A screen 16 crosses the bottom of the hood closing the opening between the hood and the vacuum box. Directly in advance of the hood the front end of the box is formed with a flaring extension 17 which terminates in a horizontally disposed thimble 18 to which I connect the grain feed spout 19 feeding to the vacuum box.

20 represents a distributing pan following the inner contour of the box at the sides and extending inwardly within the box from the thimble and forming with the top of the box a contracted discharge opening 21 which passes from side to side of the box in a

location slightly in advance of the hood. The space between the pan and the top of the box is divided by spaced vertically disposed divisional plates 22 which serve to scatter the grain coming in through the pipe 19 so that it is more or less evenly distributed throughout the full width of the discharge opening 21.

To the rear end of the vacuum box I connect a flaring extension 23 presenting an inwardly and downwardly inclining bottom 24 and the outer end of the extension is connected by means of a suction pipe 25 with the side of the fan casing to the interior of which it opens at 26.

27 and 28 represent similar air pipes extending from the ends of the hood and leading to the sides of the extension 23, their points of entrance to the interior of the extension being horizontally opposite and the ends of the pipes attached to the extension being horizontally disposed as best shown in Figs. 3 and 4.

29 represents a deflector located in the thimble 18 and designed to deflect the material downwardly toward the pan. Within the vacuum box I locate two screens 30 and 31 both of which have their edges received slidably within channel irons 32 fastened to the sides of the box, the arrangement being such that one can, by opening the door 13, withdraw the screens from the vacuum box and change them when desired. The front screen 30 inclines forwardly and downwardly, the upper end being positioned to the rear of the hood, while the lower end terminates at a cross strip 33 positioned on the bottom of the vacuum box in a location directly to the rear of the outlet spout 34 leading from the bottom of the vacuum box at the front end.

The screen 31 inclines rearwardly and downwardly, the upper end being positioned a short distance to the rear of the upper end of the screen 30 while the lower end terminates a short distance away from the inner end of the bottom 24 of the extension 23 and thereby provides an escape passage 35 for material later disclosed.

36 represents a draw-off spout leading from the bottom of the vacuum box at the rear which spout is provided with spaced upper and lower valves 37 and 38 carried by valve rods 39 and 40 which terminate in handles 41 and 42 positioned at the side of the machine.

43 is a discharge spout leading from the bottom of the fan casing to which it is tangent. The outer end of this spout can be connected with any suitable point of discharge as occasion may demand. Between the outlet spout 34 and the discharge spout 43 I locate a feeder 44 which comprises a casing 45 communicating at the top with the spout 34 and at the bottom with the spout

43 and a paddle wheel 46 rotatably mounted within the casing and carried by a rotatably mounted cross shaft 47. The paddle wheel embodies a plurality of equispaced radially extending vanes or paddles 48 contained between side disks 49 forming receiving pockets 50 for the material coming down the spout 34. The casing 45 is constructed such that the top half of the wheel has moving contact with the casing while the bottom half flares away at the front and back from the wheel providing a clearance space 51 at the front and an inclined discharge chute 52 at the rear.

53 represents a vent pipe opening to the interior of the casing in a location in advance of the spout 34.

By the arrangement herein before described it will be apparent that the vacuum box is divided by the screens into three chambers indicated at A, B and C, the feed spout 19 feeding to the chamber A and the outlet spout 34 leading from the chamber A, the draw-off spout 36 leading from the chamber B, the pipes 27 and 28 leading from the chamber A to the chamber C and the blast pipe 25 leading from the chamber C to the fan casing.

The drive for the fan and feeder can be of any suitable form. In the present instance it comprises a front suitably supported driving shaft 54 fitted with a large pulley 54' and a pair of small pulleys 55 and 55', the pulley 55 being driven by the driving belt 56, while the pulley 54' drives the pulley 9 by means of a belt 57. The pulley 55' is connected by means of a crossed belt 58 to a driving pulley 59 carried by a suitably mounted cross shaft 60 and the cross shaft is fitted with a pinion 61 which meshes with a driving gear wheel 62 secured to the end of the feeder shaft 47. This construction provides a comparatively slow feed for the feeder and effects a rotation in the direction indicated by the applied arrow in Fig. 5.

The feed spout 19 has the inner end 19' thereof stationary and supported by an upwardly extending U-shaped bar 63 extending outwardly from the vacuum box and with the outer end reinforced by angularly disposed brace bars 64. In a location just in advance of the supporting bar the feed spout is supplied with a flexible joint 65 which allows of the front end thereof being raised or lowered or swung laterally and toward the outer end the said feed spout is fitted with a flexible elbow 66 which permits of the downwardly extending end 19' thereof being swung as desired. Intermediately between the flexible connections the spout is made up from several disjointable sections so that the length of it between these points can be increased or diminished as wished.

In order to support the extending end of

the feed spout so that it can be manipulated readily by the attendant I have provided a swinging beam 67 which overhangs and supports the pipe and is swivelly supported in

5 the following way:—

Two brace bars 68 and 69 extend one from the vacuum box and the other from the bar 63 and connect at a point above the feed spout where they form a circular ring which 10 clamps around a stationary bearing plate 70 fitted with a socket 71. 72 is a carrying block bearing on the plate 70 and provided with a centering pin 73 entering the socket and fitted further with a cross opening 74 15 slidably receiving the beam. To the top of the block I secure two arms 75 and 76 fitted with eyes through which I pass stays in the nature of cables 77, the front ends of the cables being permanently anchored to the 20 front end of the beam at 78 while the rear ends are fitted with threaded extensions 79 which pass through an angle plate 80 secured to the rear end of the beam where they are provided with adjusting nuts 81.

25 The forward end of the beam carries a pulley 82 and over this I pass a rope or line 83 having one end free and the other end attached to the feed spout. By tightening up the nuts I can maintain the beam against 30 end shifting while if desired I can move the beam endwise in the block by releasing the nuts, shifting the beam and then afterward tighten up the nuts to hold the beam in the adjusted position.

35 Here it will be noticed that the beam is elevated sufficiently to clear the top of the vacuum box and that should the beam be moved backwardly one can shift back the strap 84 on the spout or can leave the strap 40 as it is and remove a section or two of the spout.

Obviously the beam relieves the weight of the outer end of the feed spout and makes it very easy for the attendant to adjust the 45 spout to suit requirements as by manipulating the line 83 he can raise or lower the spout and after having made his adjustment he can tie the line to maintain the spout in the adjusted position. The lateral 50 swinging of the spout is accommodated by the flexible connection 65 and the pivot pin 73.

The operation of the machine is as follows, 55 assuming the parts driven in order to operate the feeder and the fan, it being here understood that the fan effects a suction in the pipe 25 and a blast in the pipe 43 and that the outer end of the feed spout is placed in a wagon, hopper, car or such like containing the grain to be cleaned.

The suction produced in the vacuum box 60 by the fan draws the grain and other material in through the spout 19 and as it reaches the deflector it is deflected downwardly and 65 then afterward immediately spread by the

spreader so that it passes in through the opening 21 to the chamber A, being directed to the screen 30. This screen separates the grain, such as wheat and larger material, from the small seeds, chaff and dust, these 70 latter going through the screen into the chamber B. The separated material is fed to the spout 34 which directs it to the feeder.

The screen 31 is considerably finer than the screen 30 and it is designed to only let dust 75 and very fine dirt through to the chamber C. The other material entering the chamber B through the screen 30 is directed to the spout 36 and here it is to be noticed that one or other of the valves 37 and 38 is closed so as 80 to prevent out-draft through the spout when the machine is working. The material accumulating in this spout is removed by first closing the valve 38, then opening the valve 37 to let the material drop through and then 85 afterward closing the valve 37 and opening the valve 38 to permit the material to discharge from the lower end of the spout.

As the machine is in operation there is a strong draft through the pipes 27 and 28, 90 this draft being an upward one to the pipes from the chamber A and a horizontal one inwardly at the chamber C, the blasts from the pipes actually blowing directly against each other in the chamber. The up 95 draft from the chamber A serves to keep the surface of the screen 30 clean, preventing blanketing and it carries with it a certain amount of the foreign material suspended in the chamber A, the screen 16 being of a mesh 100 such that it will not allow wheat to go through. The material entering the hood with the upward air current is carried out through the pipes 27 and 28 and directed into the chamber C with the blast and here 105 is dropped for the greater part on to the inclined bottom 24 where it slides down through the opening 35 into the spout 36.

By directing the two side blasts into the chamber C in the manner shown I find that 110 a great proportion of the material suspended in the incoming blasts is dropped on to the bottom 24, this probably being due to the fact that the opposing blasts knock the heads out of each other, so to speak, and so 115 deposit the suspended material. The grain delivered by the spout 34 to the feeder enters the pockets of the paddle wheel and in the rotation of the paddle wheel falls down from the pocket at the underside of the wheel and 120 is caught by the inclined part 52 which delivers the grain in a falling stream across the discharge spout where it is swept ahead by the out-going blast from the fan and is delivered in the blast from the outer end of 125 the discharge spout.

Obviously the arrangement of the paddle in its casing prevents a back pressure from the discharge spout to the outlet spout. The vent 53 effects a reduction to atmospheric 130

4
pressure of any air entrapped in the passing pocket as the paddle rotates. Valves 85 and 86 are provided in the pipes 27 and 28 to allow of the control of the blast therein.

5 In connection with this machine I may herein mention that I utilize it as associated with a further machine which I term a supercleaner and which is shown and described in my co-pending application bearing Se-
10 rial No. 321,402, and filed September 2, 1919.

When the two machines are connected together the discharge spout 43 of this machine is actually the receiving spout 10 of the supercleaner.

15 What I claim as my invention is:—

1. In a grain cleaning machine, a casing, a grain feeding spout connected to the casing, a fan operatively connected to the casing and designed to effect an air blast through the casing and the feed spout, screens within the casing intermediate of the spout and fan, a discharge spout communicating with the fan, a rotary feeder associated with the discharge spout and an outlet spout for cleaned grain leading from the casing to the feeder.

2. In a grain cleaning machine, a casing, screens dividing the casing into a number of chambers, a grain feeding spout communicating with one of the chambers, a fan communicating with another of the chambers, a wind discharge spout operated by the fan, a feeder associated with the discharge spout and an outlet spout for cleaned grain extending between the casing and the feeder.

3. In a grain cleaning machine, a casing, screens dividing the casing into front, intermediate and rear chambers, a grain feeding spout leading to the front chamber, a fan communicating with the rear chamber, a draw-off spout communicating with the intermediate chamber, a blast discharge spout operated by the fan and an outlet spout leading from the front chamber and communicating with the discharge spout.

4. In a grain cleaning machine, a casing, screens dividing the casing into front, intermediate and rear chambers, a grain feeding spout leading to the front chamber, a fan communicating with the rear chamber, a draw-off spout communicating with the intermediate chamber, a blast discharge spout operated by the fan, a rotary feeder associated with the discharge spout and an outlet spout leading from the front chamber to the feeder.

5. In a grain cleaning machine, a casing, screens dividing the casing into front, intermediate and rear chambers, a grain feeding spout leading to the front chamber, a fan communicating with the rear chamber, a normally closed draw-off spout communicating with the intermediate chamber, a blast discharge spout operated by the fan, a rotary feeder associated with the discharge

spout and an outlet spout leading from the front chamber to the feeder.

6. In a grain cleaning machine, a casing, a grain feeding spout communicating with the front end of the casing, an air suction pipe communicating with the rear end of the casing, separating screens crossing the casing and dividing the same into front, rear and intermediate chambers, means for drawing off the material separated by the screens and means for effecting an upward air blast across the surface of the front screen.

7. In a grain cleaning machine, a casing, a grain feeding spout communicating with the front end of the casing, an air suction pipe communicating with the rear end of the casing, separating screens crossing the casing and dividing the same into front, rear and intermediate chambers, means for drawing off the material separated by the screens and a suction air pipe leading from the front chamber and communicating with the former air pipe and designed to effect an upward air draft across the front screen.

8. In a grain cleaning machine, a casing, a grain feeding spout communicating with the front end of the casing, an air suction pipe communicating with the rear end of the casing, separating screens crossing the casing and dividing the same into front, rear and intermediate chambers, means for drawing off the material separated by the screens, a suction air pipe leading from the front chamber and communicating with the former air pipe and designed to effect an upward air draft across the front screen and a screen guarding the end of the air pipe leading from the front chamber.

9. In a grain cleaning machine, a casing, a grain feeding spout leading to the front end of the casing, a suction air pipe leading from the rear end of the casing, separating screens passing across the casing and dividing it into a front, a rear and an intermediate chamber, means for drawing off the material separated by the screens, a hood associated with the front chamber and air pipes leading from the hood to the rear chamber.

10. In a grain cleaning machine, a casing, a grain feed spout communicating with the front end of the casing, an air suction pipe leading from the rear end of the casing, front and rear downwardly diverging cleaning screens crossing the casing and dividing it into front, rear and intermediate chambers, means for withdrawing the material caught by and deposited from the screens and an air pipe leading from the top of the front chamber to the rear chamber and designed to provide an up draft to prevent the blanketing of the front screen.

11. In a grain cleaning machine, a casing, a grain feed spout communicating with the front end of the casing, an air suction pipe

- leading from the rear end of the casing, front and rear downwardly diverging cleaning screens crossing the casing and dividing it into front, rear and intermediate 5 chambers, means for withdrawing the material caught by and deposited from the screens, a hood located on the top of the casing immediately in advance of the front screen, a screen guarding the entrance end 10 of the hood and a pair of air pipes leading from the hood to the opposite sides of the casing and opening to the rear chamber of the casing at horizontally opposite points. 12. In a grain cleaning machine, a casing, 15 a grain feed spout opening to one end of the casing at the top, an upstanding inclined screen crossing the casing, a distributing pan crossing the casing and extending inwardly of the casing from the feed spout and having the inner end thereof forming with the 20 top of the casing a contracted discharge opening opposing the screen and vertically disposed divisional plates extending between the pan and the top of the casing and designed to distribute the incoming grain 25 evenly over the pan.

Signed at Winnipeg, this 25th day of August, 1919.
